3 Claims. (Cl. 241—166)

1

My invention relates to improvements in delivery-clearing devices on roller-mills for grain and seeds, and the main object of my improvement is to prevent the goods from leaving the crushing gap in the form of small laminae and from sticking in patches to the rollers after having passed through the crushing-gap.

A number of delivery clearing-devices on roller-mills have become known in the prior art, which devices aim to break up or disintegrate the patches of goods sticking to the rollers when grinding parts of various grains and seeds. The ground goods in such prior devices either are collected in greater quantities, after having passed the rollers, by means of special arrangements, or the said devices are built with a view of subdividing the ground goods, upon delivery from the crushing-gap, into two fine streams without collecting the goods. In the first-mentioned type of such prior devices, relatively large rubbing-faces are set up between the rollers and the goods, whereby not only much grinding-flour or dust is produced, but also the rollers and the goods are excessively heated. On the other hand, one has not succeeded in practice—without collecting the goods as set forth—in so mounting the knife-beams, rigidly or resiliently, as to prevent their seizing. Thus, excessive pressures and, consequently, an undesirable excessive heating of the goods always are set up.

Such disadvantages and drawbacks shall be eliminated by the present invention by so adapting a mill beam immediately behind the roller-gap, adjustably and resiliently, that only a small goods collecting-space is formed intermediate of the rollers and said beam, and that, further, a passage for a goods-stream each is formed on either side of said beam. The goods in said space then are detained to such an extent only as to remain loose and to be continuously renewed therein in operation.

One form of invention is shown, by way of example, in the accompanying drawing, in which

Fig. 1 is a cross-sectional view through the rollers and a clearing-device on line I—I of Fig. 2, and

Fig. 2 a diagonal section on line II—II of Fig. 1.

The grinding-rollers of a conventional roller-mill are designated by 1 and 2, and the goods 3 are ground intermediate thereof. A mill beam 5 is disposed back of the crushing-gap 4 and is from 3 to 15 millimeters thick, thus forming a relatively small collecting-space 6 for the ground goods. The latter is detained in said space, and

then delivered in two streams 7 and 8 disposed on either side of beam 5. The latter, at the two ends of the rollers 1 and 2, is supported on two set-screws 9 and, at its rear end on one arm of a rockable bell-crank lever 10 pivoted to the lateral standards of the roller-mill. The beam 5 at one end is provided with a rear knife-edge, which is received in a notch 12 of the abutting-arm of bell-crank 10, whilst at the other end it 10 abuts against a face 13 of said arm, such face being indicated by a dotted line. The other arm of bell-crank 10 is biased by a helical spring 14, the other end of which is secured to a second set-screw 15. By adjusting the latter the tension of spring 14 may be regulated. The latter tends to pull bell-crank lever 10 up against two stop-screws 16 (one at each end of the mill frame) which are so set that the edges of beam 5 adjacent the rollers 1, 2 are equally spaced over their 15 entire length, from the said rollers, thus affording substantially equal delivery-gaps for the goods-streams 7 and 8. Due to the resilience of bell-crank 10, the ground goods in the collection space 6 are detained to such extent only as to remain loose and to be continuously replenished in operation.

I claim:

1. A device on roller-mills for grains and seeds adapted to prevent the goods from leaving the crushing gap in the shape of small laminae and from sticking in patches to the rollers, comprising a mill beam loosely mounted to the rear of the crushing-gap between the rollers and extending over the entire length of the latter, the forward edge of said beam projecting upwardly into said gap so as to leave a comparatively small space between said gap and rollers and a delivery-gap on each flank of said edge between the rear end of said space and said rollers, spring-loaded rockable abutting-means for the two lateral rear ends of said beam, a set-screw at each lateral end of said beam for freely supporting the latter on its web, and an adjustable stop-screw acting on each said abutting-means for adjusting the throw of the latter; the whole in such combination as to permit to detain the ground goods in the said space in loose condition and to continuously replenish same in operation.

2. A delivery clearing-device on roller-mills as set out in claim 1, and in which the two lateral ends of the mill beam are adapted as knife-edges which abut against the said abutting-means.

3. A delivery clearing-device on roller-mills as

3

set out in claim 1, and in which the mill-beam forward edge which co-operates with the said space has a thickness of from three to fifteen millimeters.

FRITZ TANNER.
